CLAIM

The ornamental design for water filter, as shown and described.

DESCRIPTION

FIG. 1 is a perspective view of the water filter, showing my new design in use,

FIG. 2 is front view of the water filter in straight position,

FIG. 3 is a left side view of the same in straight position,

FIG. 4 is a right side view of the same in straight position,

FIG. 5 is a rear view of the same in straight position,

FIG. 6 is a plan view of the same in straight position,

FIG. 7 is an underside view of the same in straight position,

FIG. 8 is a front perspective view of the same in straight position,

FIG. 9 is a rear perspective view of the same in straight position,

FIG. 10 is a front view of the same in tilted position,

FIG. 11 is a left side view of the same in tilted position,

FIG. 12 is a right side view of the same in tilted position,

FIG. 13 is a rear view of the same in tilted position,

FIG. 14 is a plan view of the same in tilted position,

FIG. 15 is an underside view of the same in tilted position,

FIG. 16 is a front perspective view of the same in tilted position; and,

FIG. 17 is a rear perspective view of the same in tilted position.

The broken lines in FIG. 1 illustrate use environment for the water filter that form no part of the claimed design.

1 Claim, 17 Drawing Sheets
